AIR SWEPT PULVERIZER HAVING AN ECCENTRICALLY ARRANGED AIR THROAT FLOW AREA

Graham W. Bice, Rosemont, Pa., assignor to The Babcock & Wilcox Company, Rockleigh, N. J., a corporation of New Jersey

Application June 20, 1945, Serial No. 600,531

6 Claims. (Cl. 241—60)

1

The present invention relates to the construction and operation of pulverizers of the type in which materials, such as coal, rock, and the like, are pulverized between one or more grinding surfaces and a relatively moving rolling grinding element or elements and the pulverized material carried out of the grinding zone in suspension in a gaseous carrier medium. A pulverizer of this general type is shown in U. S. Patent No. 2,275,595, in which the pulverizing elements are relatively movable upper and lower grinding rings between which a circular row of grinding balls is horizontally arranged and the pulverized material removed from the grinding zone by a stream of carrier air passing upwardly through an annular throat and picking up pulverized material discharged from the outer circumferential edge of the lower grinding ring.

In the operation of such pulverizers air or other gaseous medium used for the classification of pulverized materials within the pulverizer is customarily used as a carrier medium to transport the finely divided product discharged from the pulverizer to points of use or storage. When the material pulverized is coal or other solid fuel the carrier air is also used as primary combustion air in burning the fuel. Since, in the use of pulverizers of this type, particularly in direct firing installations, the capacity of the pulverizer may be varied over a wide range to accommodate the fuel requirements of the furnace served, it is also customary to change the rate of air flow proportionately or in predetermined ratio with the fuel rates delivered to the furnace. Such changes in air flow will also change the velocity of the air passing through the annular throat adjacent the discharge edge of the lower grinding ring and if the velocity is less than a definite critical value it will permit a dribble of materials, downwardly through the throat against the ascending stream of air. While it is desirable to permit a dribble of materials having a specific gravity greater than that of coal through the throat, such as for example, particles of pyrites, slate, tramp iron and the like, any loss of fuel by dribble through the throat should be avoided.

In the construction of pulverizers of the type described, the pulverizer air inlet is usually arranged for radial air delivery into an annular air chamber surrounding the throat and adapted to direct the flow of air into the lower end of the throat passage. Other pulverizer arrangements have introduced air into the air chamber at positions other than radial to the pulverizer, but in all constructions the problem has been to arrange

2

the air introduction so as to provide a substantially uniform allocation of air passing through each equal segment of throat throughout the circumference of the pulverizer.

With an unequal air flow velocity through different circumferential portions of the throat the minimum air flow through the pulverizer is limited to the critical flow velocity of air through that segment of throat having the least flow velocity of air. Such an unbalance condition of air flow through the various segments of the throat will not only limit the air flow range of the pulverizer, but may also increase the dribble through the throat particularly at low capacities. In addition such conditions may adversely affect the effectiveness of size classification within the pulverizer and cause non-uniformity in the combustibility of the air-coal mixture discharged through the individual multiple pulverizer outlets to separate furnace burners.

The principal object of the present invention is to provide a pulverizer of the type described which is characterized by an improved construction and arrangement of the parts forming the air throat of a pulverizer. A further and more specific object is to provide an improved pulverizer throat wherein the velocity and pressure of the air leaving the air throat adjacent the grinding zone of the pulverizer is substantially uniform for each segment throughout the circumference of the throat. An additional object is to provide a pulverizer throat construction which will permit a substantially uniform quantitative and qualitative discharge of combustibles from multiple pulverizer outlets. A further object is to provide a pulverizer throat construction of the type described which is characterized by its ability to permit operation of the pulverizer over an extended operating capacity range with a minimum dribble of normally pulverizable material therethrough.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation of a pulverizer constructed in accordance with the present invention;

Fig. 2 is an enlarged plan view, partly in section, of the lower portion of the pulverizer shown in Fig. 1 with some of the internal parts removed; and.

Figs. 3 and 4 are section views taken respectively along the lines 3-3 and 4-4 of Fig. 2.

The pulverizer illustrated includes a cylindrical upper housing 10 and a lower section 11 supported on a foundation 12. The lower section 11 encloses the pulverizer gear drive which includes a horizontal pinion shaft 13 arranged to drive a vertical drive shaft 14 axially arranged in the section 11 and the housing 10. The drive shaft 14 extends upwardly through bearings arranged in a base plate 15 forming the top of 15 the base section 11. The upper housing 10 is detachably secured to the base plate 15 and encloses the grinding parts of the pulverizer which comprises a drive yoke 17 of generally conical form keyed on the upper part of the drive shaft 14 and an annular lower grinding ring 18 supported on and dowelled to a flattened lower portion of the drive yoke. The upper face of the grinding ring is shaped to form a circular track for a row of rolling grinding elements 20, preferably balls of wear resistant ferrous alloy. The balls support a non-rotary upper grinding ring 21 having a circular ball track formed in its lower face. An annular spider 22 mounted on the upper ring is provided with lugs 23 arranged in guides 29 on the inner wall of the housing 10 for preventing rotation, but permitting vertical movement of the spider 22 and upper grinding ring 21. A resilient grinding pressure is exerted downwardly on the grinding parts by a number of coil springs 24 engaging the spider.

The material to be pulverized is supplied through a feed spout 25 to the inner side of the upper grinding ring 21 and the circular row of balls 20 and falls on the upper inclined surface of the yoke 17, being distributed throughout the grinding area by the rotation of the drive yoke and associated parts. Due to the effect of centrifugal force the material flows outwardly between the rings and balls, discharging therefrom at an oblique angle to the periphery of the grinding elements depending upon their rotational speed.

The pulverizer illustrated is of the air swept type wherein a stream of primary or carrier air passes upwardly at the circumferential discharge side of the pulverizer grinding zone and through a rotary classifier 26 to one or more valved outlets 27 in the top of the housing 10. The air is normally preheated and supplied under pressure by a suitable forced draft fan (not shown) through a connecting duct and an inlet 28 to an annular wind box 30 surrounding the lower part of the housing section 10. The stream of carrier air from the wind box 30 passes into the housing 10 through passages 31 into an annular space 39 in the housing 10 at the outer side of the drive yoke 17. The air stream then flows upwardly through a throat passage 32 formed between the outer side of the lower grinding ring 18 and an annular throat ring 33 mounted for radial adjustment on the inner side of the housing 10. A segmental portion of the outer throat wall is formed by a pivoted relief gate 34 which swings out to permit the passage of any large pieces of unpulverizable or foreign material, such as slate or tramp iron, into the lower portion of the housing 10. At a position subsequent to the relief gate 34, in the direction of rotation, the base section 11 is provided with a pocket or compartment 35 for the collection of material drop-

ping through the throat 32, and the gate section 34, into the lower part of the pulverizer. The compartment 35 communicates with the grinding zone through a small opening 36 in the housing base plate 15 below which a slidable gate 37 is mounted and manually operable through a rack and pinion system 38 to open and close the opening 36. The compartment 35 is periodically cleaned through a door 40.

In the operation of the pulverizer illustrated, the material to be pulverized is supplied to the inner side of the grinding elements and is subjected to the pulverizing effects of the rings and balls during its outward flow therethrough. As the pulverized material flows outwardly beyond the edge of the lower ring 18 it is picked up by the stream of air ascending through the throat 32, with the material-laden air passing upwardly to the rotating classifier 26 which separates the coarse and fine particles, the coarse particles being returned to the inner side of the ball row and the fine particles delivered to the pulverizer outlet or outlets 27. The particles of material not picked up by the annular air stream, due to their excessive size or density, fall through the subjacent part of the air throat or through the relief gate section 34 into the air entrance area at the outer side of the drive yoke 17, and thence into the compartment 35.

When pulverizers of the type described are used in a direct firing system, the amount of air supplied to the pulverizer may be substantially proportional to the amount of coal pulverized or may be in some predetermined ratio with the amount of coal. In any event, the air velocity in the throat will vary over a wide range with changes in the pulverizer load. Accordingly, at low pulverizer loads, the air velocity through the throat 32 may approach the minimum velocity necessary to maintain in suspension the mass of pulverized material occurring at the discharge side of the grinding elements, and to lift the smaller particles of that material out of the grinding zone. The heavier particles of the suspended mass will tend to drop through the air stream and into the throat, either clogging a portion of the opening or falling through into the lower part of the housing. The amount of material dribbling through the throat 32 will of course vary with the velocity of the air passing therethrough and at low pulverizer capacities the dribble may reach undesirable proportions. Such conditions may be aggravated by an unequal distribution of air flow around the circumference of the throat whereby the flow velocities through one segment of the throat may be less than that through another segment. Under such conditions the minimum total air flow to and through the pulverizer will be limited by the air velocity through that section of the throat having the lowest air flow, otherwise the total loss by dribble through the one section of throat may be disproportionate to the total air flow to the pulverizer. Such circumferentially unequal air flows will also tend to cause an unequal sizing of the pulverized material delivered by the pulverizer and, when a plurality of pulverizer outlets 27 are provided, there may be an inequality in the density of coal and air mixture delivered through each outlet and an unequal distribution of coal and air to each pulverizer outlet.

In the construction and operation of air swept pulverizers of the type described it has been customary to locate the air inlet 28 to the wind box 30 in a radial position with respect to the pul-

verizer, although the inlet may be tangential or at some intermediate position between radial and tangential. Likewise, the throat opening has been formed to provide a substantially uniform pressure drop for air flow therethrough, as disclosed and claimed in Patent No. 2,378,681 of E. G. Bailey, et al., issued June 19, 1945. In the application referred to, lugs or crickets 41 are extended inwardly from the ring 33 to a position adjacent the rotating ring 18 whereby the velocity of air flow through each segment of the throat 32 between the crickets 41 is substantially uniform throughout the vertical height of the throat. However, it has been found that regardless of the position of the air inlet the air pressure at different positions in the wind box 30 will be reduced proportionately with its circumferential spacing from the air inlet 28. Thus, with the higher air pressure available in the vicinity of the air inlet, that portion of the throat 32 will receive a greater share of the air than a correspondingly equal circumferential portion of the throat in a comparatively lower wind box pressure area.

In accordance with the present invention the air flow, and thus the air velocity, leaving the upper end of the throat 32 and entering the pulverizing zone is equalized so that the air velocity leaving one circumferential portion of the throat is substantially equal to the velocity leaving any other equal portion of the throat. This is accomplished by the construction and installation of the throat ring 33 whereby the outer circumference of the ring 33 is coaxial with the axis of the pulverizer while the inner circumference of the ring 33, which forms the outer wall of the throat passage 34, is eccentric with respect to the rotative axes of the yoke 17 and lower grinding ring 18. The crickets 41, previously referred to, are preferably cast integral with the ring 33 and their inwardly projecting sides are machined so as to be coaxial with the outer circumference of that ring.

As shown particularly in Figs. 3 and 4, the inner circumference of the throat ring 33 is formed generally by the intersection of an upper inverted frusto-conical portion 33A and a lower frusto-conical portion 33B. The conical surfaces are coaxial and eccentrically arranged with respect to the axial center line of the outer circumference of the ring 33. The surface of the upper conical portion 33A diverges upwardly and outwardly at an angle of approximately 45° from the plane of cone intersection while the lower surface 33B diverges downwardly and outwardly at an angle of approximately 75°. For uniformity in casting, the throat ring is cored so that the thickness of the walls of the ring is generally equal, except at 12 circumferentially spaced positions where internal bosses 42 are cast in the ring to provide metal for drilling and tapping to attach the ring to the housing 10 by means of the stud bolts 43. A segment of the ring 33 is omitted as shown in Fig. 2 to provide space for the relief gate 34 previously described. Preferably the open ends of the ring adjoining the gate 34 are closed by welding plate sections 44 therein to prevent an accumulation of solid materials in the ring recess as might interfere with the operations of the relief gate.

Upon installation, the throat ring is positioned in the pulverizer so that the center of eccentricity, which is intersected by the coaxial centerlines of the conical surfaces 33A and 33B, is offset from the axis of rotation of the yoke 17 on the radial centerline of and away from the air inlet 28.

This is illustrated in Fig. 2 wherein B represents the axis of rotation of the lower ring 18 and A represents the center of eccentricity. In addition, the plane of intersection of the conical surfaces 33A and 33B will be at an elevation slightly above that of the upper circumferential corner of the grinding ring 18 at the side away from the air inlet. Accordingly the radial width of the throat passage 32 in the vicinity of the air inlet will be less than the corresponding width of the throat at a position on the opposite side of the pulverizer.

The radial throat width at intermediate circumferential positions will be proportionately graduated between the minimum and maximum limits of throat width and will be equal at corresponding angular or circumferential positions on each side of the air inlet. Thus the throat width at positions 90° and 270° from the air inlet in the direction of yoke rotation will be the same and correspond substantially to the average of the maximum and minimum throat widths.

As an example of throat ring eccentricity, the design area of free throat radial width for a medium capacity pulverizer with a concentric throat is $1\frac{3}{32}$ " and with an eccentric throat the amount of eccentricity is $\frac{3}{32}$ ". Thus, the radial width of the throat 32 between the grinding ring 18 and the throat ring 33 at the air inlet is $1\frac{3}{16}$ " and at a position 180° from the air inlet the radial throat width is $1\frac{1}{8}$ ". At positions 90° on either side of the air inlet the throat width is $1\frac{3}{32}$ ".

When such a pulverizer is operated at near rated capacities, static pressure readings taken at different circumferential positions in the wind box 30, such as at positions 45, 46 and 47 indicate static pressure drops for the air flow therethrough of approximately 1.3 inches water-gauge between positions 45 and 46 and approximately 1.6 inches water-gauge between positions 45 and 47. Due to the comparatively large area of the ports 31, the static pressure drop due to the air flow therethrough is very low and of little consequence, so that the static pressure of the wind box 30 at circumferentially spaced positions is correspondingly transmitted to the annular space 39 below the throat.

Advantageously, the described construction of the throat ring 33 provides a substantially uniform air flow velocity leaving the upper end of the throat passage 32 by compensating for the unequal air pressure entering different circumferential segments of the lower portion of the throat passage.

I have found that the eccentric throat construction described will provide a substantially uniform distribution of air flow around the periphery of the lower grinding ring 18 and into the pulverized material discharging from the grinding elements. Such conditions are evidenced by static pressure readings at angularly spaced positions in the wind box 30 and throat passage 32 which indicate that the pressure and velocity of the air streams leaving the throat and entering the pulverizing zone are substantially uniform at all positions around the circumference of the pulverizer at each pulverizer operating capacity. Advantageously this throat construction permits an increased pulverizer capacity range without an excessive dribble of materials through the throat. The improved operation of the pulverizer is further evidenced by an improvement in the qualitative uniformity of the combustible mixture delivered to the burners

through multiple pulverizer outlets as the result of a balanced air flow through the pulverizing and classifying zones of the unit. Likewise, there is an essentially equal quantitative distribution of the coal and air mixture between the pulverizer discharge outlets, both of which result from the substantially uniform distribution of circumferential throat air flow.

In the claims, the word "air" is intended to generically cover any gaseous carrier medium suitable for removing pulverized material from the pulverizer in the manner described.

I claim:

1. A pulverizer comprising a closed casing, a grinding member having an upper grinding surface, said member being mounted within the casing for rotation about a central vertical axis, means for introducing material to be ground onto the upper grinding surface of the member, means cooperating with this grinding surface for grinding the material, an annular air chamber below said grinding member having a series of circumferentially spaced air inlet ports in the wall thereof, means for causing the pressure of the air delivered to said chamber to graduate downwardly in value from a position adjacent one circumferential portion of said chamber, and an annular throat ring having its central axis spaced from the central vertical axis of said rotary grinding member to define an annular throat between the grinding member and the throat ring with its radial width of circumferential opening graduated in inverse relationship to the air pressure available in the subjacent air chamber to establish a substantially circumferentially uniform air velocity upwardly through said throat for carrying away pulverized material discharged from said grinding member.

2. A pulverizer comprising a closed casing, a grinding member having an upper grinding surface, said member being mounted within the casing for rotation about a central vertical axis, means for introducing material to be ground onto the upper grinding surface of the member, means cooperating with this grinding surface for grinding the material, an annular air chamber below said grinding member, a wind box encircling said casing in communication with said annular air chamber through circumferentially spaced air ports and arranged to receive air from an inlet radial to the axis of said pulverizer, and an annular throat ring eccentrically arranged with respect to said central vertical axis to define an air throat between said ring and the periphery of said grinding member, the eccentric throat spacing being graduated in radial width to compensate for the unequal air pressures maintained in said annular chamber for a circumferentially substantially uniform air flow upwardly through said throat to carry away pulverized material discharged by said rotary grinding member.

3. A pulverizer comprising a closed casing, a grinding member within the casing for rotation about a central vertical axis, a plurality of rolling grinding elements in contact with said rotary grinding member, means for introducing material to be ground between said rotary grinding member and grinding elements, a wind box encircling said casing and having a series of circumferentially spaced air ports through the inner wall thereof in communication with the lower portion of said casing, said wind box decreasing in cross-sectional area from a radial air inlet in one side to the opposite side of said wind box, and a throat ring forming an annular throat above said air

ports between the outer side of said rotary grinding member and the inner surface of said throat ring, said throat ring being arranged eccentrically about said rotary grinding element with the width of said throat greatest at a point opposite said air inlet and proportionately graduated to be smallest adjacent said air inlet to cause a circumferentially substantially uniform velocity of air through each segment of said throat.

4. A pulverizer comprising a closed casing, a grinding member within the casing for rotation about a central vertical axis, a plurality of rolling grinding elements in contact with said rotary grinding member, means for introducing material to be ground to the inside of said rotary grinding member and grinding elements, a wind box encircling said casing arranged with a decreasing cross-sectional area from an air inlet radially arranged with respect to said pulverizer and having a series of ports through the inner wall of said wind box in communication with the lower portion of said casing, and an annular throat ring radially spaced from the periphery of said grinding ring to define an annular air throat therebetween, the side of said air throat defined by the throat ring being eccentric with respect to said central vertical axis with the radial width of said air throat greatest at a point circumferentially opposite said air inlet and graduating equally on each semi-circular side of said throat circumference to its smallest radial width adjacent said air inlet to circumferentially equalize the air flow velocity upwardly past the discharge side of said grinding member.

5. A pulverizer comprising a closed casing, a grinding ring mounted within the casing for rotation about a central vertical axis and having an upper grinding surface and an outwardly and downwardly flaring peripheral surface, means cooperating with said upper grinding surface to grind material therebetween, means for rotating said ring, a feeder arranged to deliver material to be ground to the inside of said grinding surface, an annular throat ring having an outwardly and downwardly flaring inner surface radially spaced from the periphery of said grinding ring to define an annular air throat therebetween having a pair of downwardly diverging opposite sides, the diverging side of said throat defined by the throat ring being eccentric with respect to said central axis, said eccentricity of said throat ring being arranged to circumferentially equalize the air flow leaving said annular throat by having the throat portion of greatest pressure drop of air flow through the throat corresponding with the highest static pressure of air entering the throat, crickets mounted on said throat ring and proportioned and arranged to subdivide said throat into a plurality of circumferentially adjacent passages each of substantially uniform cross-sectional flow area throughout its height, and means for introducing air upwardly through said throat to carry away air suspended pulverized material discharged by said grinding ring.

6. A pulverizer comprising a casing enclosing a rotary grinding member, rolling grinding elements on said grinding member, means for delivering material to be pulverized to the inner side of said grinding elements, means for directing an annular stream of air upwardly past the outer side of said grinding member to sweep up pulverized material discharging therefrom including an annular throat ring cooperating with the outer periphery of said grinding member to define therebetween an annular air passage of substantially fixed flow area, and means for maintain-

ing a substantially uniformly distributed air velocity circumferentially through said throat which includes spacing the axis of said throat ring from the axis of said rotary grinding member to compensate by graduated pressure drop of air flow through said throat for the different pressures of the air entering circumferential portions of the annular air throat passage.
